REFECTORY TABLE SLIDE

Charles Lee Bolick, Hickory, N. C.

Application March 24, 1948, Serial No. 16,669

2 Claims. (Cl. 311—71)

1

This invention relates to a refectory table in which a frame-work having legs is provided with centrally disposed means on the table frame for supporting the table top, thus providing a slot between the opposed sides or ends of the table top, in which slots are adapted to be nested extension leaves, and which leaves are provided with slides, and also suitable guiding members are mounted on the table frame cooperating with the slides on the bottom of the leaves, for guiding the same from a nested position beneath the table top to an extended position where they will occupy the same plane as the main table top.

It is an object of this invention to provide a refectory table having extension leaves at the two sides thereof which are adapted to be pulled out from beneath the table top and be guided into a position where they will occupy the same plane as the table top and have the inner edges thereof abutting against the edges of the main table top. The table frame and the nestable leaves have cooperating guiding means for guiding the leaves from nested position to a position where the leaves will occupy the same plane as the table top and abut against the opposed ends of the table top.

Although in the drawings the main table is shown as having the refectory leaves mounted at each end thereof, the main portion of most refectory tables are made so that the breadth is greater than their length and the refectory leaves are usually mounted at the sides of the table top, but these refectory leaves can be mounted to slide out at the ends of the table, as well as at the sides of the table, as the same principle is involved.

Some of the objects of the invention having been stated, other objects will appear as the description proceeds when taken in connection with the accompanying drawings, in which

Figure 1 is an isometric view of my improved refectory table showing one of the leaves extended and one nested and with portions broken away to show one of the slide assemblies;

Figure 2 is a longitudinal sectional view taken along the line 2—2 in Figures 1 and 11;

Figure 3 is a vertical sectional view taken along the line 3—3 in Figure 2;

Figure 4 is a sectional view taken along the line 4—4 in Figure 11;

Figure 5 is a view similar to Figure 4, but showing the leaf in nested position;

Figure 6 is a vertical sectional view taken along the line 6—6 in Figure 5;

Figure 7 is a vertical sectional view similar to

2

Figure 4, but showing a modified form of the invention;

Figure 8 is an enlarged detail view of the central portion of Figure 7, with parts broken away;

5 Figure 9 is a view similar to Figure 8, but showing the position of parts as the refectory leaf is being slightly pulled outwardly prior to a nesting operation;

Figure 10 is an enlarged vertical sectional view 10 taken along the line 10—10 in Figure 7;

Figure 11 is a top plan view of the table showing one leaf extended and one leaf nested;

Figure 12 is a vertical sectional view taken along the line 12—12 in Figure 4;

15 Figure 13 is a vertical sectional view taken along the line 13—13 in Figure 11; and

Figure 14 is a detail, with parts omitted, showing the restricted portion of slot 35, and its junction with slot 34.

20 Referring more specifically to the drawings, the numerals 10 and 11 indicate side frame members of a table while the numerals 12 and 12' indicate the end frame members of the table which are suitably secured to uprising legs 15, 16, 17 and 18.

25 Secured on top of the side frame members 10 and 11 by any suitable means, is a board 20 on top of which is suitably secured a main table top 21.

The table top 21 has its opposite edges projecting 30 beyond the edges of the board 20, thus providing recesses 22 and 22' beneath each end of the table top 21 to receive nesting or refectory leaves 25 and 25'. In the drawings the refectory or nesting leaf 25 is shown in extended position

35 while the leaf 25' is shown in nested position, but, of course, it is to be understood that in use, possibly both of the refectory leaves 25 and 25' will be moved to extended position when the table is desired to be extended as to length or

40 width depending upon the shape of the main table top 21.

The main portion of the table having been described, the means for mounting the refectory leaves will be described, and the left-hand end 45 of the table, such as shown in the drawings, will be described and like reference characters will apply to the right-hand end with the prime notation added. Also, since the sliding mechanisms on both sides of the table at each end thereof

50 are identical, except for opposite hand arrangement of the same on each end of the table, like reference characters will apply to all of the slide assemblies.

Secured to the lower surface of the main table top 21 by means of screws 26 and removed from

the side edges thereof, are angle clips 30 which extend downwardly and have suitably secured thereto, as by rivets 27, a frame guide member, preferably in the form of a channel bar 31, which has its other end secured by screws 28 to the inner surface of the end frame member 12 of the table. This frame guide member 31 is closed at both ends, not only to strengthen the same but to facilitate its being secured to the angle clip 30 and the end frame member 12. The frame guide member 31 has a horizontally disposed slot 33 therein which projects to near the outer end thereof and has an upwardly directed slot portion 34 and a reversely bent slot portion 35. To the lower surface of the refectionary leaf 25 are secured by screws 29, leaf guide members 39, preferably in the form of channel bars, which are closed at both ends to add rigidity to the same. The leaf guide members 39 have sliding movement in notches 36 disposed in the end frame member 11, and extend inwardly beneath the outer edge of the table top 21 and through the slots 38 and their inner ends are adapted to fit into cavities 38 in the outer edge of the board member 20 when the leaf 25 is extended.

The leaf guide member 39 is positioned alongside the outer side of the frame guide member 31 and the leaf guide member 39 has an irregular slot extending longitudinally thereof which has an inner portion 49 which is slightly inclined upwardly as it is directed towards the center of the table, and at the outer end of the slot portion 49 it is merged with an upwardly and outwardly inclined slot portion 42 which merges with a horizontally disposed slot 43 disposed immediately below the top web of the leaf guide member 39.

The frame guide member 31 has fixedly mounted therein a stud 45 comprising a circular portion 46 adapted to have movement in the slot portions 40, 42 and 43 and this stud or rivet has an enlarged head portion 47 which prevents dislodgement of the portion 46 from the slot portions 40, 42 and 43. The leaf guide member 39 has likewise mounted therein a stud or rivet 50 which has a portion 52 adapted to slidably move in the slot portions 33, 34 and 35 and has an enlarged head 54 which confines the portion 52 within the slot portions 33, 34 and 35.

In cutting the slot portions 33, 34 and 35, there is left an unsupported tongue 60 and in order to properly support this tongue 60 I provide a rivet 61 which penetrates a spacer collar 62 which is disposed between the tongue 60 and a plate 63 which is welded between the side angles of the frame guide member 31, and the rivet 61 has its ends bradded on the outer surfaces of the tongue 60 and the plate 63 to thus properly support the tongue 63 to keep it from being bent laterally. It will be noted that the head of the rivet in the right-hand side of Figure 3 is countersunk so as to avoid its interfering with relative sliding movement between the leaf guide member 39 and the frame guide member 31 whose proximate sides are close to each other.

It will also be noted that the inner ends of the leaf guide members 39 are sloped inwardly and downwardly to facilitate their moving inwardly and through the slots 38 in the board member 20, and also to facilitate their moving under the board member 20 when the refectionary leaves 25 are being moved to nested position.

In Figures 7 to 10 inclusive a modified form of the invention is shown in which like reference characters will apply to like parts, the main difference being that in order to releasably lock the refectionary leaves 25 in extended position, I

provide a stud 70 on the tongue portion 60 of frame guide member 31 and on this stud 70 I pivotally mount a spring clip 72 which is of restricted U-shape in form and has a reversely bent end 73. When the refectionary leaf 25 is moved outwardly in the slot portion 35 to nest the same, the spring clip 72 is moved to the position shown in Figure 9 and when the leaf 25 is brought outwardly and raised to the position shown in Figure 4, being pushed inwardly, it will cause the member 72 to occupy the position shown in Figure 8.

Another difference in the structure shown in Figures 7 to 10 inclusive is that, instead of having a rivet as described in the preceding figures, the rivet 45, having the portion 46 for sliding movement in the slots, and having the enlarged portion 48 for confining the rivet in the slot, has the portion 46 of slightly less diameter, and this portion 46 is surrounded by a roller 75 to cause ease of operation. It is thus seen that as head 48, positions the spring member 72 as shown in Figure 8, when the leaf 25 is in the position shown in Figure 4, whereas when the refectionary leaf 25 is pulled outwardly to where it can be lowered to nested position, the head 48 will cause the spring clip member 72 to occupy the position shown in Figure 9.

The slots 33 and 34 and the outer portion of slot 35 are wide enough for the portion 46 or roller 75 to have free movement therein, however, in order to produce a binding effect on the roller 75 or portion 46 during, say the last half inch of travel in slot 35, the slot 35 is restricted as at shoulder 37 so roller 75 or portion 46 will have a tight fit therein to thus bind the refectionary leaf in operating or extended position and prevent its being moved easily outwardly away from the edge of the table top 21.

It is thus seen that I have provided a refectionary table in which the slides are metallic and thus not subject to swelling and shrinking during changes in weather, and also one which is positive in operation and having means whereby the refectionary leaves can be locked in extended position and whereby they can quickly be nested in a matter of a few moments of time.

By having a slot in each of the frame guide members and the leaf guide members, it is possible to provide a refectionary table having a much shorter main table top than is possible where both slots are in only one of the guide members.

In the drawings and specification there has been set forth a preferred embodiment of the invention, and although specific terms are employed, they are used in a generic and descriptive sense only and not for purposes of limitation, the scope of the invention being defined in the claims.

I claim:

1. In a refectionary table slide frame consisting of a frame guide member having inner and outer ends and having a J-shaped guiding slot cut therein, the outer end of which is directed upwardly and then inwardly, a leaf guide member disposed alongside the frame guide member and having an inwardly projecting portion provided with a slot near its inner end which extends slightly downwardly as it progresses toward the outer end of the leaf guide member and then projects upwardly and outwardly and then extends horizontally outwardly toward the outer end of the leaf guide member, a guiding pin secured on the frame guide member and having movement in the slot in the leaf guide member and a second guiding pin secured on the leaf guide member and having movement in the slot in the

frame guide member, the two slots in the frame guide member and the leaf guide member being in super-posed offset relation substantially throughout their length when the slidable leaf guide member is in extended position relative to the frame guide member, the lower wall of the short leg of the J-shaped slot having a cam surface thus diminishing its width to elevate the leaf guide member as its guiding pin is moved toward the closed end of the short leg of the J-shaped slot.

2. In a refectory table slide frame consisting of a frame guide member and a leaf guide member, the frame guide member having a J-shaped slot therein disposed in a vertical plane with the long leg thereof being lowermost and the upper leg thereof being near the outer end of the frame guide member and directly inwardly, the frame guide member having a slot extending outwardly and downwardly, then upwardly and then outwardly, and a pair of guiding pins for the frame guide member and leaf guide member, there being one disposed in each of the members and having movement in the slot in the adjacent member, the two slots in the frame guide member and the

leaf guide member being in super-posed offset relation substantially throughout their length when the leaf guide member is in extended position, and movable latching means provided adjacent the short leg of the J-shaped slot for engaging the guiding pin disposed in the J-shaped slot for latching the leaf guide member in extended position.
